United States Patent Office

Des. 223,553

Patented May 2, 1972

223,553

ASHTRAY

Manuel Valverde, 419 E. 10th St., Seymour, Ind. 47274

Filed Sept. 16, 1969, Ser. No. 19,166

Term of patent 14 years

Int. Cl. D27—03

U.S. Cl. D85—2

Fig. 1.

Fig. 2.

Fig. 3.

Fig. 4.

Fig. 5.

FIG. 1 is a front elevational view of an ashtray, showing my new design;

FIG. 2 is an elevational view looking from the left of FIG. 1;

FIG. 3 is an elevational view looking from the right of FIG. 1;

FIG. 4 is a top plan view; and

FIG. 5 is a rear elevational view thereof.

I claim:

The ornamental design for an ashtray, as shown.
